UNITED STATES PATENT OFFICE.

AUGUSTINE DAVIS, JR., OF COVINGTON, KENTUCKY.

BOLSTER FOR TANK WAGONS.

Application filed August 15, 1923. Serial No. 657,486.

To all whom it may concern:

Be it known that I, AUGUSTINE DAVIS, Jr., a citizen of the United States, and a resident of Covington, in the county of Kenton 5 and State of Kentucky, have invented a new and useful Bolster for Tank Wagons, of which the following is a specification.

The object of this invention is to provide a bolster for tank wagons of very light yet 10 strong construction. These bolsters are required to support a heavy load, of a highly inflammable nature in the case of gasoline, and must resist the strains of running, collision, etc. The successful construction of 15 such bolsters from relatively light sheet metal presents, therefore, a problem, and the herein disclosed combination of form and structure in an integral design has been arrived at as the result of special study and 20 experiment.

In the accompanying drawings illustrating the invention:

Fig. 1 is a plan view of a bolster embodying the invention;

Fig. 2 is an elevation; and

Figs. 3, 4 and 5 are vertical sections on the lines 3—3, 4—4 and 5—5, respectively, of Fig. 2.

The bolster A is made practically of a 30 single sheet of steel, vertically disposed in the position which it is intended to occupy and horizontally elongated. The top of the sheet is incurved to form an integral cradle 1 for the tank, and at opposite sides of the 35 cradle the sheet is extended to produce lateral wings 2, for the support of running-boards. The tops 3 of these wings are straight, as is also the bottom edge 4 of the sheet extending below and for some distance 40 at opposite sides of the cradle. At either side of the straight bottom, the lower edges 5 curve upward to give a buttress formation to the wings.

The thickness of the bolster is obtained 45 by pressing flanges at one side of the plane of the vertical web so as to extend continuously along the straight and curved portions of both the upper edges 1 and 3 and the lower edges 4 and 5. The upper flange 50 is marked 1^a and 3^a, and the lower flange 4^a and 5^a, and it may be noted that the portion 1^a of the upper flange, at the cradle, diminishes in width from the ends to the mid-

dle. This top flange is extended, however, and caused to project at both sides by the 55 application of a metal strip 6 running the length of the cradle curve and centralized over the web. The parts of the composite double flange 1^a, 6 are united at the edges, as indicated at 7, by welding, either oxy- 60 acetylene or electric. In this way a broad cradle is produced, which is greatly stiffened, owing to the relation of the welded layers.

As thus constructed the bolster requires 65 for vertical bracing only a flat piece 8 of small area, which is welded at top and bottom to the central portions of the edges of the flanges 6 and 4^a, by which it is spaced away from the body web.

Additional angle pieces 9 are welded to 70 the inner face of the web, in the wings, beneath the flanges 3^a. The horizontally projecting top flanges of these pieces lie against the under sides of the flanges 3^a, and both are perforated to receive the terminals of 75 the straps (not shown) which hold down the tank.

Other angle pieces 10, having their horizontal flanges at the bottom, are welded to the same face of the web, immediately over 80 the bottom flange 4^a, the double flanges at these points being perforated for the bolts 85 which will secure the bolster to the sills of the frame or mounting.

What I claim as new is:

1. A bolster for tank wagons comprising 90 a single vertical elongated sheet having upper and lower flanges pressed therefrom at one side only, the top of the sheet and the top flange being formed as a downwardly incurved cradle, and a curved seat plate united to said cradle and projecting laterally at both sides of the plane of the web.

2. A bolster for tank wagons comprising 95 a single vertical elongated sheet having upper and lower flanges pressed therefrom at one side only, the top of the sheet and the top flange being formed as a downwardly incurved cradle, and a curved seat plate welded 100 to said cradle and projecting laterally at both sides of the plane of the web, in combination with a brace piece spaced from the web and welded to the cradle and to the lower flange.

AUGUSTINE DAVIS, JR.
